UNITED STATES PATENT OFFICE.

PAUL J. SIMMEN, OF INDIANAPOLIS, INDIANA.

TRAIN-DESPATCHING SYSTEM.

1,257,412.

Specification of Letters Patent. Patented Feb. 26, 1918.

Application filed November 18, 1911. Serial No. 861,112.

To all whom it may concern:

Be it known that I, PAUL J. SIMMEN, a citizen of the United States, residing at Indianapolis, in the county of Marion and State of Indiana, have invented a new and useful Train-Despatching System, of which the following is a specification.

My invention relates to train despatching and signaling systems.

10 In the operation of railroads, whether steam or electric, it is necessary that the train movements of the road, or a division thereof, be directed by some one man, the despatcher, who has information as to the location and movements of all trains. To accomplish this, there must be communication between this man and the trains, both for giving him the necessary information and giving the train operatives the necessary directions. This communication has usually been obtained by human intermediaries, such as telegraph operators.

15 It is the object of my invention to remove as far as possible any chance of erroneous judgment, and to prevent absolutely any faulty execution, on the part of any human instrumentality used in the operation of the railroad, while at the same time allowing the greatest possible freedom of action so long as it is within safe limits; to eliminate the necessity for any human intermediary, who generally forms the weakest link in the chain, between the despatcher and the train operatives; to increase the facility of operation and the track capacity; to provide better discipline among the employees; and to do this by a system which is at once inexpensive to install and maintain, efficient and reliable in operation, not subject to easy derangement, and in its preferred form requires no movable parts at stations along the road.

20 In carrying out my invention, there are provided a signal controller located at the train despatcher's office and having its parts locked and interlocked to prevent dangerous operations thereof by the despatcher, train signals controlled by said controller, and a graphic recording device located at the despatcher's office and controlled automatically by the movements of the trains in response to said controller. The recording device gives the despatcher full, constant, and immediate information as to 25 both the location and the movements of all trains under his control; and also serves as a

permanent record, which may be used, for example, by higher officials of the road for disciplinary purposes. With this information graphically before him, the despatcher is not liable to make any error in judgment; but if he should, the locks and interlocks of the signal controller positively prevent such error from becoming effective in action. The interlocks of the controller parts are controlled by the adjacent parts. The controller locks and the record are controlled in common by the movements of the trains in response to the signals produced by the signal controller, and may be made to cease their actions without such movement only by the coöperation of the despatcher and a train operative.

The various novel features of my invention will appear from the description and drawings, and will be particularly pointed out in the claims.

In the drawings, Figure 1 shows diagrammatically a preferred embodiment of my invention; Fig. 2 is a front elevation of the despatcher's board of the system of Fig. 1, showing the signal controller and the graphic record in their preferred relationship; Fig. 3 is an end elevation of such board; Fig. 4 is an enlarged end elevation of the signal controller, the casing being in section substantially on the line 4—4 of Fig. 2; Fig. 5 is a fragmentary sectional view showing some of the parts of Fig. 4 in a different position; Fig. 6 is a fragmentary section substantially on the line 6—6 of Fig. 4; and Figs. 7 to 11 inclusive are diagrammatic views showing some modifications.

The railway system illustrated has a single track 10, over which there is traffic in both directions. Along this track, which may be assumed to run east and west, are a number of stations A, B, C, D, E, F, . . . These stations may be actual railway stations or other convenient dividing points between blocks, station A being assumed to be a terminal of the road or of one division thereof. At each station there is a siding 11, which in the diagrams is shown disproportionately large in relation to the distance between two adjacent stations, or the blocks; and also a "home" third rail section 12 and a "distant" third rail section 13 for each direction of movement, the third rail sections for each direction of movement conveniently being on the right hand side of the track, and the distant third rail section

being engaged by the shoe 15 of a car before the home third rail section 12. Preferably the siding 11 is located between the third rail sections for the two directions of movement.

In the preferred arrangement shown in Fig. 1, the four third rail sections at each station are all connected in common by wires 12^a, to a line wire 16 leading through a fuse 32 and a relay coil 17 to one arm 18 of a double pole switch 19 of the signal controller. There is a switch 19 for each station A, B, C, . . . these switches being shown directly above their corresponding stations in the diagram of Fig. 1. When the arm 18 engages either of its coöperating buttons 20, which are connected in common by a wire 20^a through a switch 31 to one side of a battery 21, the third rail sections 12 and 13 for the corresponding station are energized; so that if the shoe 15 of a car is in engagement with one of such third rail sections, the circuit is completed from the latter through the car to ground, the side of the battery 21 which is not connected to the buttons 20 being also grounded through wire 21^a. This circuit, beginning at battery 21, includes wire 21^a, ground, wheels of car, wires 21^b, 21^c and 15^a on car, shoe 15, third rail section 12 or 13, wire 12^a, fuse 32, relay 17, arm 18, button 20 and wire 20^a to battery 21. The connection on the car between the shoe 15 and the ground preferably includes a relay magnet 22, which, when energized, lifts and holds lifted its armature 23, thus completing a circuit from a local battery 24 for the green or safety lamp 25 through the wires 25^a and 25^b, connecting said lamp with the battery 24. As the shoe 15 passes off the third rail section it swings into engagement with a contact 26, which is connected by a wire 26^a through a magnet 27 to a button 28 also engaged by the armature 23 when the latter is in its upper position, thus completing a holding circuit for the magnet 22 from the battery 24 through the arm 23, wire 26^a, contact 26, shoe 15 and wire 15^a. Thus the armature 23 is maintained in its upper position even after the shoe 12 has passed off an energized third rail section, so that the green light is retained burning.

When the shoe 15 next passes upon a third rail section, it is separated from the contact 26, thus deenergizing a magnet 27 in the wire 26^a; whereupon the armature of the latter springs back and strikes a bell 29 to call the attention of the engineer or motorman to the fact that a third rail section has been reached and that there is a possible change in signals. If the third rail section thus engaged by the shoe 15 is alive, the magnet 22 is maintained energized by current from the battery 21, as above explained, and the green safety light 25 is maintained burning. However, if this third rail section

is not alive, the magnet 22 is deenergized upon the separation of the shoe 15 and contact 26 and the armature 23 drops to break the circuit for the green or safety light and to complete the circuit for the red or danger light 33 by engaging the contact 23^a which is connected by wire 23^b with the battery 24, which is connected to said armature 23, the lamp 33 being located in the circuit. This danger light remains burning even if the car passes beyond the deenergized third rail section, as the holding circuit on the car, above described, is now open. The signal can be changed from the red light to the green light only by the engagement of the shoe 15 with an energized third rail section, and from a green light to a red light only by the engagement of the shoe 15 with a dead third rail section, but under such condition the change occurs immediately. By opening the switch 31 the despatcher can make all the third rail sections dead; this may be desirable for emergency use, as in violent storms.

In addition to its arm 18, each switch 19 has a second arm 35, which is movable with the arm 18 and may be connected through the wires 35^a and 35^b, the switch 36 operated by the relay coil 17, wires 36^a and common line 36^b, with one terminal of a battery 37. The arm 35 is movable from its middle or off position into engagement with either button 38 or 39. These buttons are connected to the operating magnets of the east and west bound relays 41 and 40, respectively, by the wires 38^a and 39^a, each button controlling the closing magnet 42 for the relay for the block next in advance and the opening magnet 43 for the block next in the rear, if any, the two magnets being connected by a wire 42^a, for relays 40 and 43^a for relays 41. Thus, assuming the arm 35 on the button 39, the circuit beginning at the battery 37, is through the wires 36^b and 36^a, the switch 36, the wires 35^b and 35^a, the arm 35, the wire 39^a, the magnet 42, the wire 42^a, the magnet 43, the wire 43^a, connecting said magnet 43, and the line wire 43^b leading back to the battery 37. For clearness in the diagram, as well as for convenience in practice, as illustrated in Fig. 2, all the east bound relays 40 are arranged in one line and all the west bound relays 41 in another line. The east and west bound relays 40 and 41, when closed, complete the circuits of locking electro-magnets 44 for the switches 19 which control their closing movements. One of these circuits may be traced as follows: beginning at the battery 37, through the line 43^b, the relay 40, the wire 40^a, the magnet 46, the wire 47^a, the clock switch 45, and the wire 45^a to the battery 37, or from the battery 37, through the wires 43^b and 43^a, the relay 41, the wire 41^a, the magnet 47, the wire 47^a, the switch 45 and the wire 45^a.

to the battery 37. The locking magnet circuit can be traced, for example as follows: beginning at the battery 37, thence through the wire 43^a, the relay 40, the wire 44^a, the 5 unlocking magnet 44, and the wire 36^b to the battery 37.

In the diagram of Fig. 1, this record sheet is shown as moving upwardly, though in actual practice it is preferred that it move 10 downwardly, as indicated in Figs. 2 and 3. The movement of the record sheet 49 is preferably obtained by an electro-magnet 50 operating a pawl and ratchet device 51 and controlled by the clock switch 45, the circuit 15 for the magnet 50 comprising the battery 37, wire 43^b, a wire 50^a, magnet 50, a wire 50^b, line wire 47^a, switch 45, and wire 45^a to battery 37. The record sheet 49 is ruled with parallel lines transverse to its direction of 20 movement. These lines represent the time they actually pass the row of perforating needles, this time preferably being marked along the edges of the sheet. The rate of travel of the sheet may be designed to suit 25 the particular case. The record sheet is also ruled with longitudinal parallel lines denoting the various stations A, B, C, . . . along the road. The spaces between the longitudinal or station lines represent the 30 blocks between stations. For each block there is an east bound perforating magnet 46 and a west bound perforating magnet 47, these two magnets being located so that their needles 48 will mark the record sheet on that 35 side of the center of the corresponding block thereon on which is the station line representing the station from which said block is entered. Thus the perforating magnets 46 and 47 for the block B—C will perforate 40 the record sheet somewhat to the left and to the right respectively of the center of the space between the station lines B and C. In addition to the block perforating magnets 46 and 47, there is a station perforating 45 magnet 52, with its perforating needle 48, which is energized through the corresponding switch 36 whenever the corresponding relay coil 17 is energized. The circuit is as follows: Beginning with the battery 37, the 50 current passes through wires 36^b and 36^a, switch 17, wire 35^b, a wire 52^a, magnet 52, thence by wires 50^a and 43^b back to battery 37.

The perforating magnets 46, 47, and 52 55 are arranged in separate tiers, as best shown in Fig. 3, the station perforating magnets 52 being located in front of the sheet 49 and the other perforating magnets behind it. The needles 48 of these perforating magnets 60 are preferably separate from the armatures 53 thereof, and carry weights 54; so that when pushed toward the record sheet 49 by their respective armatures 53 they will pierce the paper by their own momentum, and then, 65 by the action of the springs 55, spring

slightly away from the sheet, the attracted position of the armatures 53 being arranged to permit this. Since each magnet 52 is energized when a car shoe 15 is on an energized third rail section of the corresponding station, the despatcher can tell by the springing back of an armature 53 to its normal or unattracted position just when a car leaves a corresponding station; that is why the magnets 52 are put in front of the record sheet. The record sheet is preferably made in a roll 56, whence it passes over the roller 57 operated by the magnet 50, under a friction roller 58, in a straight line to the roller 59, thence to the roller 60, and from there 70 to a spring winding roller 61 of any usual construction.

Each switch 19 is mounted on a rod 65 operated by a handle 66, and the various switches 19 are arranged side by side within 85 a case 67 which may either be made of glass or provided with a glass top 68. Each rod 65, carrying its switch arms 18 and 35, is spring pressed inward, or to the right in Fig. 4, by a coil spring 69, but may be 90 moved forward against the action of such spring to bring the switch arms out of the plane of the coöperating buttons 20, 38 and 39 into engagement with a plate 70, shown as a pair of contact buttons in Fig. 1. All 95 the plates 70 are grounded through an electric bell 71, by means of the wire 71^a, for a purpose which will hereinafter appear. The springs 69 are preferably located within fixed nipples 72, concentric with the corresponding rods and mounted on a fixed bar 73 extending longitudinally of the casing 67. A pin 74 projects from the front face of each nipple 72, and may engage any one of three holes 75 in a segment 76 fixed on the 100 switch operating rod 65. The segments 76 are arranged all in the same plane, and are so shaped, as best shown in Fig. 6, that the upper ends of two adjacent switches 19 cannot be thrown toward each other; that is, 105 that such two switches cannot be so thrown as to admit oppositely traveling cars in the same block at the same time. The general arrangement and operation of the segments 76 is indicated diagrammatically in dotted 110 lines in Fig. 1. In order to turn any switch 19 from one position to another, it is necessary that the rod 65 first be pulled forward to disengage the pin 74 from the hole 75 with which it was in engagement. This 115 movement is less than the thickness of the segments 76. Each segment is also provided with a pair of notches 77 into which the lock 78 controlled by a locking magnet 44 may be moved when the switch 19 is in either extreme position. For diagrammatic convenience, the notches 77 are shown on the top of the segment in Fig. 1, though in actual practice the notches are preferably in the lower edge of said segments as shown in 120 125 130

Figs. 4, 5, and 6. These notches may be closed, to prevent the lock 78 from being moved into them, by bars 79 operated by a spring push button 80 in the corresponding rod 65.

Assume that a car or train 81 is to start from the terminal station A and proceed eastward, passing on the road a car or train 82 coming westward. The dispatcher will 10 set his switches 19 for stations A and B, say, to the right and those for stations D, E, and F, say, to the left, as indicated in Fig. 1. This locks the switch 19 for station C, so that it can be moved neither to the right nor 15 to the left, and provides for a meeting of the two cars at station C. The car 81 at the terminal station A receives its proceed or clear signal, given by the movement to the right of the switch 19 for such station, at 20 say 4:12 p. m., the shoe of such car then being on the distant third rail section 13 for said station. This signal, as already explained, causes the lighting of the green light 25 in such car. The closing of the circuit through the car also energizes the relay coil 17 for such station, thus closing the switch 36 and completing the circuit for the station recording magnet 52 of station A and, through the switch arm 35 and button 39, that of the closing magnet 42 of the east 25 bound relay 40 for the block A—B. At the moment the motorman receives his signal to proceed, the station perforating magnet 52 for station A makes a dot on the line A, thus recording both the presence of the car at that station and the giving of the signal to the motorman, and practically simultaneously therewith the east bound perforating magnet 46 for the block A—B begins to 30 mark the record sheet at the proper place, the circuit of this magnet being completed through the corresponding relay 40 and the clock switch 45. The closing of the relay 40 also causes the energization of the corresponding locking magnet 44, to lock the switch 19 for station A in its east bound position. The magnet 46 makes a mark or perforation on the record sheet every time 35 the circuit is closed by the clock switch 45, the record sheet being moved forward continually by the solenoid 50 and the same clock switch 45. Thus a continuous mark or cut is produced by the magnet 46 on the sheet 49 while the relay 40 remains closed.

55 As the car 81 proceeds eastward, after leaving the distant third rail on which it was originally, it soon passes the home third rail section for station A, thus ringing the bell 29 and making a second mark or dot on the 40 station line A of the record sheet. By the distance between these two dots, the dispatcher can tell the speed with which the car travels the distance between the two third rail sections 12 and 13, of this or any other 45 station, and by the position of the armature

53 for the station perforating magnet 52 of station A he can tell when the car passes off a third rail section. Sometimes the distant third rail sections may be omitted. As the car proceeds from station A to station B, the green or safety light in such car remains lighted in a manner already explained, the east bound perforating magnet 46 continues to perforate the record sheet to indicate the presence of the car in the block 70 A—B, and the switch 19 for the station A is locked in east bound position by the locking magnet 44. Thus the switch 19 for station A cannot be thrown back to off position, and by the interlocking action of its segment 76 75 with the corresponding segment 76 of the adjacent switch 19 for station B the latter switch cannot, even if the operator should try to do it, be thrown to west bound position; i. e., to a position to admit a west 80 bound car into the block A—B.

When the car 81 reaches station B, its shoe 15 engages the distant third rail section 13 for such station. The lifting of the shoe by this engagement separates it from the contact 26, deenergizing the magnet 27 to ring the bell 29 and call the motorman's attention to a possible change in signals. The switch 19 being already in east bound position, this completes a circuit from the battery 21 95 through the contact 20, the switch arm 18, the relay coil 17, the wire 16, and the third rail section 13, all of station B, and thence through the shoe 15 and the magnet 22 on the car, to ground, thus maintaining the 100 green light on the car burning and causing the closing of the switch 36 for said station. The closing of the switch 36 causes the perforating magnet 52 for station B to make a dot on the line B on the record sheet 49, and 105 also completes a circuit through the switch arm 35 and button 39 for station B to the closing magnet 42 of the east bound relay 40 for the block B—C and the opening magnet 43 for the east bound relay 40 of the 110 block A—B, whereupon said two relays are moved to closed and open positions respectively. The opening of the relay 40 deenergizes the east bound perforating magnet 46 for block A—B and the locking magnet 44 115 for the switch 19 of station A, thus causing the cessation of the record for block A—B and the unlocking of the switch 19 for station A. The closing of the relay 40 for block B—C causes the locking of the switch 120 19 for station B by the corresponding locking magnet 44, and energizes, through the clock switch 45, the east bound perforating magnet 46 for the block B—C. The latter now begins its recording, which it continues until the car 81 has passed eastward out of the block B—C. When the car passes the home third rail section for station B, the bell 29 is rung and a second dot made on the 125 line B of the record sheet.

When the car 81 reaches station C, the third rail sections of which are deenergized because the switch 19 for such station is in its middle position, the lifting of the shoe 15 by a dead third rail section causes the deenergization of the magnet 22, which drops its armature 23, thus lighting the red light 33 on the car and extinguishing the green light 25. At the same time, and whenever the shoe 15 is lifted by a third rail section, the bell 29 is rung by the deenergization of the magnet 27, thus calling the motorman's attention to the fact that his signals may be changed. If, regardless of the danger signal, the motorman proceeds past this station, the fact that he has received no signal to proceed is recorded on the record sheet by the absence of any perforation on the corresponding station line. The motorman now rings up the despatcher by the magneto ringer on his telephone 83, which is preferably located in his cab. The circuit extends from the telephone 83 by the wire 15^a through the shoe 15, the third rail section 12 or 13, the wire 12^a, and the wire 16 to the despatcher's office, whence it passes through one of the condensers 84 and thence by wire 84^a to the despatcher's telephone 85 and through a relay coil 86 to ground. The despatcher now talks over his telephone 85 directly to the motorman at his telephone 83, and gives verbal orders directly to him; a record of these orders may be kept on a phonograph. The alternating currents for telephoning and for the magneto ringing are prevented from interfering with the signal by the inductances in the latter, and the direct currents used for the signal circuits do not interfere with the telephone or ringing circuits because of the condensers 84 therein. A similar condenser 87 may also be arranged between the motorman's telephone 83 and the shoe 15.

In the meantime, the car 82 has been proceeding westward, making its record on the record sheet 49 and receiving its proper signals on the way; and has reached the east end of the station C, say. Let us assume that the car 82 has reached said station before the car 81 did. The motorman on the car 82, ringing up the despatcher because of the red signal he has received, is told to take the siding 11 at such station, but before doing so to give a release ring so that the operator may release the magnetically locked switch 19 for station D, the last live station the car 82 has passed. This release ring is a mere ringing of the telephone magneto on the car 82, which energizes the relay coil 86 at the despatcher's office and thus closes the switch 88. While this switch remains closed, the despatcher may push the proper push button 80 to complete a circuit for the opening magnet 43 of the west bound relay 41 of the block C—D. This circuit

then comprises battery 37, wire 88^a, switch 88, main wire 88^b, branch 88^c, button switch 89, wire 43^a, opening magnet 43, main wire 43^b, wire 43^c and battery 37. To obtain this release, it is necessary for the motorman and despatcher to coöperate, the despatcher pushing the button 89 while the motorman is ringing his magneto ringer. If desired, however, a switch 90 can be placed in shunt to the electro-magnetically operated switch 88 for use in emergency.

The car 82 having passed on to the siding 11 at station C, and the switch 19 for station D having been unlocked by the coöperation of the despatcher and the motorman, said switch 19 at station D may be moved to off or to east bound position, thus unlocking the switch 19 at station C and allowing it to be swung to east bound position. The east bound car 81 at station C, now receiving the proper signal and starting the proper record, may now proceed eastward past the car 82 on the siding. The switches 19 at stations D, E and F may also be set to east bound position for the car 81, which, under the control of the despatcher, proceeds on its way to its destination, or until another car is encountered, which may be passed in like manner. The car 82 now backs off the siding 11 at station C after the car 81 has passed. Upon reaching the home third rail section for that station, it receives a clear signal, the receipt of which and the presence of the car at that third rail section being recorded by the station perforating magnet 52 for station C, and proceeds on its way westward.

In order to maintain his record complete, the despatcher, when he operates the switch 19 of station C as above described to allow the car 81 to proceed eastward, pushes in the button 80 of such switch and thus closes the slots 77 by the bars 79. This prevents the locking of such switch by the magnet 44 while the button 80 is held in. As soon as the car 81 has started eastward and has begun its record for section C—D, the despatcher, still holding in the button 80, moves the switch 19 of section C to westward position, so that when the car 82 starts westward from station C its movements will be recorded. This movement of the switch 19 of station C from eastbound to westbound position does not interfere with the record of the car 81 in section C—D.

Thus the despatcher has a complete record before him on the record sheet of the movements of both cars 81 and 82 and can tell precisely when they arrive at any station and when they leave it. In case the despatcher desires communication with a motorman at any time, he simply moves to or leaves in its middle position the switch 19 for the station which the motorman is approaching, so that the motorman upon ar-

riving at such station will receive a danger signal and will call up the despatcher for instructions. The interlocking segments 76 on the switches 19 prevent the despatcher 5 from sending two cars into a block from the opposite ends thereof, even should he be disposed to do so. The locking magnets 44 prevent a locked switch 19 for any station which has been passed by a car from being 10 thrown from the position in which it was required to be in order to allow the car to pass that station until the car has reached the next station, unless by the coöperation of the despatcher and a motorman.

15 When a switch 19 is thrown from any position to another, the arm 18 necessarily engages the coöperating contact plate 70, which, in the diagram of Fig. 1 is shown as divided into two contact buttons located respectively between the middle position and the two contact buttons 20. Thus in passing from one position to another, the switch arm 18 connects the corresponding wire 16 through the bell 71 to the grounded side of 25 the battery 21. If this wire 16 is crossed with another of the wires 16 and the latter happens to be energized, a circuit is completed from the battery 21 and such energized wire 16 through the first-named wire 30 16, the switch arm 18 of plate 70 and the bell 71 to the grounded side of the battery 21, and the resultant ringing of the bell tells the despatcher of the cross between the two wires 16. This furnishes a continual test for 35 these wires, for if there is a cross between any two of them or between any one and any foreign source of E. M. F., the despatcher in his manipulation of the switches 19 will always discover it in a very short time.

40 Although the arrangement illustrated in Fig. 1 is now preferred by me, various other arrangements may be used instead. Some of these alternative arrangements are shown in Figs. 7 to 11, inclusive. In Fig. 7, instead 45 of a single switch arm 18 there are separate switch arms 18' and 18'', which are connected through separate relay coils 17' and 17'' to the east and westbound third rail sections, respectively, at the west and east ends 50 of a block; that is, at adjacent stations. The two switches 18' and 18'' are interlocked by interlocking segments 76' and 76'', which prevent the two switches from being closed simultaneously to complete a 55 circuit from the battery 21 to the third rail sections controlled thereby. This gives what may be called a block control rather than a point control; and it requires twice as many line wires, there being two for each station, 60 as does the arrangement shown in Fig. 1.

The switches 36' and 36'' operated by the relay coils 17' and 17'' control the proper relay magnets 42 and 43 independently of any switch operated with the switch 18' and 65 18''; so that the switch arms 35 of Fig. 1

can be entirely omitted in this modification. The relay coils 17' and 17'' also control directly the proper station perforating magnets 52, the two coils 17' and 17'' for the same station controlling the same perforating magnet 52. These connections are shown in a simple form in Fig. 7.

70 The arrangement shown in Fig. 8 differs from that shown in Fig. 7 in that there is a common line wire for all the third rail sections at a station, the differentiation being obtained by supplying the east bound third rail sections with direct current from a battery or direct current generator 21' and the west bound third rail sections from an alternating current generator 21''. Inductances 91 and condensers 92 are placed in the direct current circuits and the alternating current circuits respectively to prevent interference between the two kinds of current. Interference between the telephone or magneto circuits and the alternating current signal circuits is prevented by properly choosing the frequencies used and designing the apparatus to respond only to the proper frequencies.

80 The arrangement of Fig. 9, like that of Fig. 7, differs from that of Fig. 1 in that there are two wires 16' and 16'' to each station instead of one. Here these wires lead to separate relay coils 17' and 17'', as in the arrangement of Fig. 7, and are connected to contact buttons 20' and 20'', the single switch arm 18 for each station being connected directly to the battery 21. The switch 95 arms 18 are interlocked by segments 76 in the same manner as in Fig. 1. Since the east and west bound third rail sections are separately controlled, the switch arms 35 may be omitted, for the switches 36' and 36'' control the proper relay coils 42 and 43 and the proper station perforating magnets 52 in the same manner as in Fig. 7.

100 Fig. 10 differs from Fig. 9 in substantially the same way as Fig. 8 does from Fig. 7, 110 the east bound third rail section being supplied with direct current and their circuits containing suitable inductances 91, and the west bound third rail section being supplied with alternating currents and their 115 circuits containing a suitable condenser 92. Figs. 9 and 10 differ from Figs. 7 and 8 respectively in that the former are point or station control systems and the latter block control systems.

120 The arrangement of Fig. 11 closely resembles that of Fig. 1, but dispenses with half of the wires 16. The same wire 16 is used for the third rail sections at two stations, which are preferably adjacent stations, one of these stations being supplied through an inductance 91 with direct current from the battery 21' and the other through a suitable condenser 92 with alternating current from an alternating current 125 130

generator 21". In this modification, as in that of Fig. 1, the switch arms 35 are provided, there being but one relay coil 17 for all the third rail sections at a station.

5. While I have shown my invention rather complete in a preferred modification, and diagrammatically in several other modifications, it is not limited to the arrangements shown or any of them. For instance, instead of having the signals on the car, as illustrated in the preferred arrangement shown, any other suitable signal, preferably of the normal danger type, may be used. My invention is capable of wide variation, and certain features of it can be used without others, or with substitutes for others; so I aim to cover all modifications which do not involve a departure from the spirit and scope of my invention as set forth in the following claims.

What I claim is:

1. In combination, a railroad divided into blocks, means for giving power to operate signals for cars or trains at the dividing stations between blocks, signals on the cars operated by said means, means at a central point for normally locking the signal-giving means of the various stations and locking said means for a station when a car or train has passed such station, and is still in the adjacent block, and means for operating the locking means to release the signal-giving means while the car or train is in said block.

2. In combination, a railroad divided into blocks, controlling means for giving power to operate signals for cars or trains at the dividing stations between blocks, means at a central point for normally locking the signal-control means of the various stations and locking said means for a station when a car or train has passed such station and is still in the adjacent block to prevent a change of signals, and means for holding the said locking means while the car is in said block.

3. In combination, a railroad divided into blocks, controlling means for giving power to operate signals for cars or trains at the dividing stations between blocks, and means for normally locking the power-giving means for a station when a car or train has passed such station and is still in the adjacent block, and means requiring the coöperation of a man at the car and a man at the power-giving means for causing said locking means to become inoperative.

4. In combination, a railroad divided into blocks, means for controlling a signal to a train or car at the entrance of each block, interlocking means between the signal-controlling means for different stations between blocks, and means controlled by the interlocking means for recording the movements of the cars or trains in response to the signals.

5. In combination, a railroad divided into blocks, means for recording the movements of the cars or trains, a signal-controller comprising a plurality of switches for controlling signals to cars or trains at the entrance to the various blocks and controlling the recording means, and interlocking mechanism between said switches.

6. In combination, a railroad divided into blocks, means controlled by the movements of the cars or trains for making a record of such movements, a signal controller comprising a plurality of switches for controlling power to operate signals for cars or trains at the entrances to the various blocks, the movement of said switches also controlling the recording means and interlocking mechanism between said switches.

7. In combination, a railroad divided into blocks, automatic means dependent upon the movements of the cars or trains for recording such movements, car-carried signals, a signal and recording means controller comprising a plurality of controlling members for controlling the operation of said signals at the entrances to the various blocks, interlocks between said controlling members, means for normally preventing the movement of any of said controlling members from a predetermined signal controlling position after a car or train has received such signal and while it is still in the block covered by such signal, and means for moving said preventive means from an operative to an inoperative position while the car is still in said block.

8. In combination, a railroad divided into blocks, automatic means dependent upon the movement of the cars or trains for recording such movements, traffic controlling mechanism, a controller for the traffic controlling mechanism and recording means comprising a plurality of controlling members for governing the operation of said traffic controlling mechanism at the entrance to the various blocks, and interlocks between said controlling members.

9. In combination, a railroad divided into blocks, automatic means dependent upon the movements of the cars or trains for recording such movements, vehicle signals, a signal and controlling means controller comprising a plurality of controlling members for causing the operation of said signals at the entrances to the various blocks, interlocks between said controlling members, and means for preventing the movement of any of said controlling members from a signal producing position after a car or train has received such signal and while it is still in the block covered by such signal.

10. In combination, a railroad divided into blocks, a record sheet, means controlled by the movements of cars or trains on the

- railroad for making a graphic record on such sheet of the progress of such cars or trains, power operated signals to direct the movements of the cars or trains on the railroad, means adjacent the record sheet for controlling the operation of such signals and the operation of the recording means, and interlocking mechanism between the various parts of said signal controlling 65 means.
11. In combination, a railroad divided into blocks, one or more cars or trains on said road, an electrically controlled signaling device on each car or train, a collector 70 carried by each car or train and controlling said signaling device, a conductor adjacent the railroad at the entrance to each block and engageable by the collector of a passing car or train, a signal controller comprising a plurality of switches each of which controls the energization of a conductor at one of said block entrances, interlocking means between said switches, and means within the sight of the operator of 75 the signal controller and controlled by the movement of said switches for automatically recording the movements of the trains.
12. In combination, a railroad divided into blocks, vehicles on said roads, an electrically controlled signaling device on each vehicle, a collector carried by each vehicle and controlling said signaling device, a conductor adjacent the railroad at the entrance to each block and engageable by the collector of a passing vehicle, a signal controller comprising a plurality of switches, each of which controls the energization of a conductor at one of said block entrances, interlocking means between said switches, 80 and means for causing a continuation of a signal produced on a vehicle upon the engagement of the collector on the vehicle with the conductor adjacent to the road after such engagement has ceased and until 85 a later similar engagement takes place.
13. In combination, a railroad divided into blocks, cars on said road, an electrically controlled signaling device on each car, a collector carried by each car and controlling said signaling device, a conductor adjacent the railroad at entrance to each block and engageable by the collector of a passing car, a signal controller comprising a plurality of switches each of which controls 90 the energization of a conductor at one of said block entrances, interlocking means between said switches, means within sight of the operator of the signal controller and controlled by the latter, for recording the giving of the signals and the movements of the cars, and means for causing a continuation 95 of a signal produced on a car upon the engagement of the collector on the car with the conductor adjacent to the road after such engagement has ceased and until a later similar engagement takes place.
14. The combination with a block, of signal controlling means for the block, a plurality of recorders for the block, means controlled by the signal controlling means for 100 controlling one recorder, and means for controlling another recorder, controlled by the controlling means for the first recorder.
15. The combination with a block, of a signal, electrical means for controlling the signal, a plurality of recorders, and mechanism for operating the recorders, including a relay for said recorders controlled by the signal operating means, said operating mechanism also including means for continuing the operation of one recorder beyond that of the other.
16. The combination with a railway block section, of a signal, electrical controlling means for the signal, including a circuit, a recorder, controlling means for the recorder, including a circuit, a relay controlled by the signal controlling circuit and controlling the recorder controlling means circuit, and switch mechanism common to both circuits.
17. The combination with a railway block section, of a signal, controlling means for the signal, a recorder, a circuit including the recorder, a lock for the signal controlling means, and common means for controlling the lock and the recorder circuit.
18. The combination with a plurality of blocks, of a car signal, electrical mechanism for actuating the car signal upon the passage of the car into each block, including at a central station a controller for each block, a plurality of recording elements at said central station, means outside the car for separately actuating the different recording elements and including a plurality of controllers, certain of which are moved by the passage of the car into the different blocks, others being movable with said central station controllers.
19. The combination with a plurality of blocks, of a car signal, electrical mechanism for actuating the car signal upon the passage of the car into each block, including at a central station a switch for each block, a plurality of electrically operated recording elements, one for each block, an electric circuit outside the car for each recording element, and including an electrically operated controller, and circuits, each controlled by the movement of the car for actuating the corresponding of said electrically operated controllers.
20. The combination with a plurality of blocks, of a car signal, electrical mechanism for actuating the car signal upon the passage of the car into each block, including at a central station a switch for each block, recording elements, one for each block, an

- electric circuit outside of the car for each recording element, and including an electrically operated controller and a manually operated controller, and an electric circuit 5 for each block having means for actuating the electrically operated controller for one of the recording element circuits, said block circuits being controlled by the movement of the car into the corresponding block.
- 10 21. The combination with a plurality of blocks, of a car signal, a plurality of direction recorders for each block, located at a central station, means at the central station for selecting from the direction recorders 15 corresponding to each block, the recorder that is to be operated for each block, and means associated with the selecting means for controlling the operation of the car signal.
- 20 22. The combination with a plurality of blocks, of a car signal, means for operating the signal upon the entrance of a car into a block, a plurality of direction recorders for each block, located at a central station, 25 means at the central station for selecting from the direction recorders of each block the recorder that is to be operated for that block, and means associated with the selecting means for controlling the operation 30 of the signal, said last-named means effecting the same control of the signal irrespective of which recorder is selected.
23. The combination with a plurality of blocks, of a block recorder for each block, 35 a direction recorder for each block, a car signal, electrically operated mechanism for controlling the car signal upon the entrance of the car into each block, electrically operated mechanism for actuating each block 40 recorder as the car enters a block, electrically operated mechanism for actuating a direction recorder while the car is in the corresponding block, and means controlled by the car for throwing one of the direction recorders out of operation and another into operation as the car passes from one block to the next.
24. A railroad divided into a plurality of blocks, means at each block for giving a 45 clear signal upon the entrance of a car into each block in either direction and also giving a danger signal at each block, and mechanism for actuating said signal controlling means to give clear signals simultaneously to cars moving in opposite directions in spaced blocks, said means preventing the giving of a clear signal to a car in a block between said spaced blocks.
25. A railroad divided into a plurality of blocks, means at each block for giving a 50 clear signal upon the entrance of a car into such block in either direction and also giving a danger signal at each block, and interlocking signal controlling mechanism at a
- signal station for the signal giving means of 65 a plurality of blocks, for the giving of clear signals to cars moving in opposite directions simultaneously in spaced blocks and preventing the giving of a clear signal at a block between said spaced blocks. 70
26. A railroad divided into a plurality of blocks, means at each block for giving a clear signal upon the entrance of a car into such block in either direction and also giving a danger signal at each block, mechanism 75 for actuating said signal giving means to give clear signals simultaneously to cars moving in opposite directions in two spaced blocks, and means operating therewith to lock the signal actuating mechanism to cause 80 the giving of a danger signal at a block between certain of said spaced blocks as long as the signal giving means of said spaced blocks are set in a predetermined relation at clear.
27. A railroad divided into a plurality of blocks, electrical means for giving at each block clear signals to cars moving in opposite directions and also giving a danger signal, a central station switch mechanism for putting the said signal giving means at each block into safety condition, and mechanism for maintaining the signal giving means at a block in danger condition whenever the means for certain blocks on opposite sides thereof are in a predetermined relation at safety condition. 85
28. A railroad divided into a plurality of blocks, electrical means at each block, for giving clear signals and a danger signal 90 to cars moving in opposite directions, a plurality of central station switches for setting the respective block signal-giving means at clear and danger, interlocking devices moving with the switches for maintaining the signal giving means at a block at danger whenever the means at certain blocks on opposite sides thereof are set in predetermined relation at clear. 95
29. A railroad having a plurality of 100 blocks, an electrically operated car signal, electric means for operating the signal at each block and including a circuit, electrically operated recording means outside the car, a circuit including the recording means, and a controller for the recording means circuit located in the signal circuit.
30. A railroad having a plurality of 105 blocks, means for giving a signal at each block, including an electric circuit, a recorder for each block including an electric circuit, means for controlling the respective signal circuits, and means operated by the closing of the signal circuits for controlling the respective recording circuits. 110
31. A railroad having a plurality of 115 blocks, means for giving a signal at each block, a recording mechanism, and mecha-

- nism controlled by the signal giving means of a given block for causing the recording mechanism to be operated when a car enters that block, and stops its operation when the car enters a succeeding block.
32. A railroad having a plurality of blocks, means for giving a signal at each block, a recording means for each block, and mechanism controlled by the signal giving means of each block for causing the recording means for that block to be operated and stopping the operation of the recording means of the block preceding it.
33. A railroad having a plurality of blocks, means for giving a signal at each block, a recording mechanism, means for operating the recording mechanism, and mechanism controlled by the signal giving means for initiating the operation of the recording mechanism by its operating means, and effecting a continuation of the operation of the recording mechanism thereby after the action of the signal giving means ceases.
34. A railroad having a plurality of blocks, means for giving a signal at each block, a recorder for each block, means for operating the recorder, and mechanism controlled by the signal giving means at each block for initiating the operation of the recorder at that block by its operating means, and effecting the continuation of the operation of the recorder thereby after the action of the signal giving means ceases.
35. A railroad having a plurality of blocks, electrical means for giving signals at each block, a recorder for each block, and means for separately operating each recorder independently of the other recorders, said recorder operating means including controlling devices respectively controlled by the signal giving means.
36. A railroad having a plurality of blocks, electrical means for giving signals at each block, a recorder for each block, and means for separately operating each recorder independently of the other recorders, said means including a controlling device controlled by the signal giving means of the same block for throwing the recorder into operation, and a controlling device controlled by the signal giving means of another block for throwing the recorder out of operation.
37. A railroad having a plurality of blocks, electrical means for giving signals at each block, including a circuit for each block, an electrically operated recorder for each block, actuating means for the various recorders, including electric circuits, and controlling means for said recorder operating circuits including electrically operated switches controlled by the signal circuits.
38. A railroad having a plurality of blocks, cars operating on the railroad and carrying electrically operated signals, and signal controlling means, electrical means at each block for controlling the signals, including a circuit for each block that temporarily includes the signal controlling means on a car located in said block, an electrically operated recorder for each block, and means for separately controlling the operation of each recorder independently of the other recorders, said means including the controlling devices that are included in the signal giving circuits and are operated when signals are given.
39. A railroad having a plurality of blocks, means for giving a signal at each block, a plurality of recorders for each block, and means controlled by the signal giving means for effecting different operations of the recorders of said block.
40. A railroad having a plurality of blocks, means for giving a signal at each block, a plurality of recorders for each block, and means controlled by the signal giving means for effecting a momentary operation of one recorder and a continuing operation of the other recorder.
41. A railroad having a plurality of blocks, electrical means for giving a signal at each block, including an electric circuit, a plurality of electrically operated recorders for each block, actuating means for one of the recorders of each block, including an electric circuit and a switch controlled by the signal circuit for that block, and actuating means for the other recorder of each block, including an electric circuit, means for periodically energizing the same and an electrically operated switch having controlling means located in the first-mentioned recorder circuit.
42. The combination with a railway, of a recording apparatus and electrical controlling mechanism for the recording apparatus including means for giving intermittent electrical impulses, said means being controlled by a car passing along the railway, and said controlling mechanism also including operating means for the recording apparatus that is set in operation by the intermittent impulses and continued in operation between said impulses.
43. The combination with a railway, of a recording apparatus and electrical controlling mechanism for the recording apparatus including means for giving intermittent electrical impulses as a car passes along the railway, said mechanism also including operating mechanism for the recording apparatus that is set in operation by one of said impulses and is stopped by another.
44. The combination with a railway divided into sections, of a recorder for each section, electrical operating means for each recorder, means for giving an electrical im-

5 pulse as a car passes each section, and means controlled by the impulse given at a section to set the recorder for that section in operation and controlled by the impulse at another section to stop the operation of said recorder.

10 45. The combination with a railway divided into sections, of a recorder for each section, electrical operating means for each recorder, means for giving an electrical impulse as a car passes each section, and means controlled by the impulse given at a section

to set the recorder for that section in operation and stop the operation of a recorder for a different section.

In witness whereof, I have hereunto set my hand and seal at Indianapolis, Indiana, this 17th day of November, A. D. one thousand nine hundred and eleven.

PAUL J. SIMMEN. [L. S.]

Witnesses:

G. B. SCHLEY,
A. M. LAYDEN.
